UNITED STATES PATENT OFFICE.

LEROY J. MARTEL, OF CENTRAL FALLS, RHODE ISLAND.

ENGINE-MUFFLER.

1,354,834.

Specification of Letters Patent.

Patented Oct. 5, 1920.

Application filed October 13, 1919. Serial No. 330,486.

To all whom it may concern:

Be it known that I, LEROY J. MARTEL, a citizen of the United States, residing at 22 Park street, Central Falls, in the county of Providence and State of Rhode Island, have invented certain new and useful Improvements in Engine-Mufflers, of which the following is a specification.

My invention relates to improvements in 10 mufflers for gas or gasoline engines, or internal explosion engines, and is also applicable to the ordinary steam engine, and the purpose of my invention is to provide a muffler that will effectually silence the sound 15 of the explosion or exhaust without creating back pressure, and in which the ingress and egress of the gases are adjustable from the outside of the muffler.

These objects are accomplished by the 20 mechanism disclosed in the drawings accompanying this application, in which—

Figure 1 is a vertical longitudinal section through the center of the muffler.

Fig. 2, a vertical cross-section on the line 25 A—A of Fig. 1, and

Fig. 3, a detail of the adjusting device.

The same letters refer to the same parts throughout the several drawings.

In Fig. 1, *t* represents the body of the muffler in the usual cylindrical form, having the heads *x*—*x'* secured thereto by bolts or other suitable means. *a* represents the inlet from the engine, and *w* the outlet from the muffler. *d*—*d'* are two diaphragms within the body of the muffler perforated as shown with a plurality of holes *e*—*e'*. Integral with the diaphragms *d*—*d'*, and forming a portion thereof, is a hollow cylinder *m* located near the central axis of the muffler. Within this cylinder *m* is located a plunger *n*, having a conical head *c* adjacent to the inlet *a*. This plunger *n* is itself in hollow cylindrical form and within it is placed with a sliding fit a second plunger *o* having the conical head *s* adjacent to the outlet *w*. The plunger *n* slides easily within the cylinder *m* and the plunger *o* slides easily within the plunger *n* and each of the plungers is capable of movement independent of the other.

The inlet *a* terminates within the muffler in the cone-shaped orifice, or seat, *b* and the outlet *w* at its inner end terminates in a similar cone-shaped receptacle *u*, the angles of *b* and *u* being the same as the respective angles of the cones *c* and *s*. In the plunger *n* is securely screwed the stem *i* which pro-

jects radially outward from said plunger and terminates in the head *B*; while the plunger *o* is provided with a similar stem *h* securely screwed to *o* and terminating without the muffler in the head *B'*; and the sliding movements of the plungers *n* and *o* are governed by these stems *h* and *i*.

The shell of the muffler is slotted at *r'*—*r* so as to permit the longitudinal movements 65 of the stems *i*—*h* and their respective plungers. In order to allow this longitudinal movement, the core or cylinder *m* is also slotted at *g* and *r* and the outer plunger *n* has a similar slot *p* for the movement of the 70 stem *h*.

As the plungers *n* and *o* are capable of longitudinal movement within the muffler, it is important that when a suitable position has been established for the cone-shaped 75 heads *c* and *s* they should be capable of being fixed in position so as to prevent accidental moving. This fixation is secured by the device shown at *y*—*z*, seen best in section in Fig. 2. These members *y* and *z* consist of cylindrical or other suitably shaped blocks perforated for the sliding therein of the stems *i* and *h*, and having serrated lower surfaces. Fixed upon the exterior of the muffler where the stems *i* and *h* come out are the members 85 *k''*—*k'''* which are in form superficially of a hollow rectangle fastened to the outer wall of the muffler as shown best in Fig. 3 and having upon the two longitudinal upper faces serrations fitting those of the blocks *y*—*z*; 90 these blocks being equal in width to the transverse width of the members *k''*—*k'''*. Between the heads *B*—*B'* of the stems *i*—*h* and the upper surface of the blocks *y*—*z* are the springs *E*—*E'* operating to keep the 95 blocks *y*—*z* in place after adjustment by means of the serrations aforesaid.

y' and *z'*, Fig. 2, are wings upon the blocks *y*—*z* by means of which these blocks may be disengaged from the serrations in 100 *k*—*k'* when adjustment is being made and the springs *E*—*E'* force said blocks into the serrations when these wings are released. As the rectangular openings in *k*—*k'* would permit the escape of gases, the slides *f* are 105 provided which are fixed upon the stems *i*—*h* and slide with it in the longitudinal openings in *k*—*k'*, thus preventing the escape of gases at these points.

By the foregoing description it will be 110 seen that the cone-shaped heads *c*—*s* may be brought into any desired relation with the

seats *b*—*u* and adjusted and fixed in position from the exterior of the muffler by means of the stems *i*—*h* with their respective heads. Any desired freedom of ingress and egress of the steam or gases is thus secured and the respective heads *c*—*s* may be easily and readily adjusted so as to provide the highest possible efficiency in the muffler.

In my drawing I have shown the stems 10 emerging from the muffler 180 degrees apart; in practice, however, these stems may be located at any desired angle with each other from 25 to 180 degrees.

While I have shown the plungers as terminating in conical heads, this shape is not vital to the operation of my invention but I deem it the most efficient form for said heads. Thus a spherical form of head may be used without departing from the principle of my invention. The inner ends of the inlet and outlet must, of course, conform to the shape of the plunger heads.

Having now described my invention, what I claim and desire to secure by Letters 25 Patent is:—

1. A muffler for engines consisting of a hollow receptacle having an inlet and an outlet; movable plungers located within the receptacle, said plungers being respectively 30 adjustable in relation to their distance from said inlet and said outlet, and means for adjusting the same from the outside of the muffler, substantially as set forth.

2. A muffler for engines comprising a hollow receptacle having an inlet and an outlet; movable plungers located within the muffler and adjustable with respect to said inlet and said outlet, the heads of said plungers being adapted to conform to or fit into 40 the inner ends of said inlet and outlet respectively; and means for adjusting said plungers from without the muffler, substantially as described.

3. A muffler for engines consisting of a hollow receptacle having an inlet and an outlet; a movable plunger located within the muffler; the head thereof being adapted to fit or conform to the inner end of the inlet of said muffler and a like plunger having a 50 head adapted to fit or conform to the inner end of the outlet of said muffler; each of said plungers having a stem fixed therein and

projecting therefrom outwardly through the external wall of the muffler, said stems serving to adjust the position of the plungers 55 with reference to the inlet and outlet of the muffler, substantially as described.

4. A muffler for engines consisting of a hollow receptacle having an inlet and an outlet; a movable plunger located within the muffler, and having a head adapted to fit or conform to the inner end of the inlet of said muffler, and a like plunger having a head adapted to fit or conform to the inner end of the outlet of said 60 muffler; each of said plungers having a stem fixed therein and projecting therefrom outwardly through the external wall of the muffler, said stems serving to adjust the position of the plungers with reference to the 65 inlet and outlet of the muffler; and means for securing said plungers in any desired position within the muffler, substantially as described.

5. A muffler for engines consisting of a hollow receptacle having an inlet and an outlet; a movable plunger located within the muffler; the head thereof being adapted to fit or conform to the inner end of the inlet of said muffler and a like plunger having a head 70 adapted to fit or conform to the inner end of the outlet of said muffler; each of said plungers having a stem fixed therein and projecting therefrom outwardly through the external wall of the muffler, said stems serving to adjust the position of the plungers with reference to the 75 inlet and outlet of the muffler; and means for securing said plungers in any desired position within the muffler, substantially as described.

In testimony whereof I affix my signature in presence of two witnesses:

LEROY J. MARTEL.
